United States Patent Office.

ANSON H. PLATT, OF PHILADELPHIA, PENNSYLVANIA.

Letters Patent No. 78,607, dated June 2, 1868.

IMPROVEMENT IN LAMP-BURNERS.

The Schedule referred to in these Letters Patent and making part of the same.

Be it known that I, ANSON H. PLATT, of the city and county of Philadelphia, and State of Pennsylvania, have invented a new and improved Kerosene-Burner; and I do hereby declare the following to be a full and exact description of the same.

Since the first introduction of kerosene into use, it has been a great desideratum to invent an argand-burner, (by which is meant a burner with a round wick, and a central and circumferential current of air,) which could be adapted to ordinary glass founts now in use, but heretofore two very serious obstacles have prevented the accomplishment of this end.

First; in order to secure the central current of air, a perpendicular aperture through the whole fount was necessary, and this was found to be impracticable in glass founts, and to get up metallic founts, expressly for the purpose was altogether too expensive to admit of general adoption into use.

Secondly, to regulate or raise and lower the wick in an argand-burner required a very complicated and very expensive device, which, with the first-mentioned obstacle, although the argand is universally admitted to be the best of all light-producing structures, has prevented it from being adopted into general use.

The important feature in my invention is, that I have completely overcome these heretofore insurmountable obstacles to the general use of the structure, and produced a burner, which, though strictly argand in all its practical effects, can, nevertheless, be readily applied to any glass fount now in use, without even a change of dollars, and will cost but very little if any more than the ordinary burners now in the market.

Figure I represents the burner entire and ready for use,

Figure II is a vertical section, made at right angles with the base, and showing the arrangements of the internal parts, and

Figures III and IV are horizontal sections, made near the base, to show the workings of the regulators in raising and lowering the wicks.

In the first place, I make use of two cylinders, slightly tapering upward from their bases, and the smaller placed within the larger, with sufficient space between them to admit the wick, as shown in Fig. II, *e e* being the cut edges of the outer cylinder, and *f f* those of the inner; these cylinders extending down through the perforated plate *k k* and the burner-case *S S*, and being firmly attached by their bases to the screw-plate *5 5*, and extending upward to near the top of the deflector *h h*, *9* representing the open centre through which the central current of air passes to the flame.

I use two distinct wicks, of equal and uniform width and thickness, which, when properly inserted between the cylinders, which constitute the wick-tubes, precisely fill the space at the top or upper ends, and, as the cylinders flare downward, there must necessarily be a triangular space upon opposite sides of the cylinders, which is not filled by the wicks, the base of this triangular space being down, and the apex at the upper end of the cylinders.

I next cut out this triangular space in the cylinders, between the wicks, from the base upward, from one-half to three-fourths of its length, as seen at *b b*, Fig. II, and close up the cut edges to prevent leakage from the wicks, and secure the structure from combustion and explosion, and these triangular spaces, thus cut out upon opposite sides of the two cylinders, afford a free admission of air from without to form the central current of air within, Fig. II, *9*, which is indispensable to an argand.

In the structure of very large argand-burners, where a greater central current of air might be needed, than could be secured through the triangular spaces *b b*, Fig. II, I make two separate semicircular wick-tubes, Fig. IV, *3 3*, of equal and uniform width, and insert one end of them in the screw-plate, *5 5*, of the burner-case *S S*, Fig. II, with their bases set apart, Fig. IV, *3 3*, sufficiently to admit the necessary quantity of air, and place the upper end or edges in contact, so as to form a cylindrical flame, and still leave the whole triangular space, from base to top, open for the admission of air, and cut through the inner plate of the tubes to allow the wheel to come in contact with the wick, as seen, Fig. II, *c c c c*.

In order to regulate the wicks when cylinders are used, as shown in Fig. II, I pass a shaft, Fig. III, *4 4*, through the triangular open space *b b*, Fig. II, and give the end *6*, Fig. III, a stationary attachment, while the other end, *4 4*, has a lateral motion in a horizontal slot, and a milled head as the means of moving it.

To this shaft, in the centre of the inner cylinder, is attached, transversely to it, and perpendicularly to the cylinder, a notch-wheel, Fig. II, 4, and opposite the notched edges of this wheel there is a slot or hole, *c c c c*, Fig. II, cut through the inner cylinder, so that by pressing the wheel to either side and turning it, it will come in contact with the wick, and move it up or down at pleasure.

When the semicircular tubes are used instead of cylinders, I cut through the inner plate of each tube and apply the wheel as in the case of the cylinders, as seen in Fig. IV.

In very large argands, where one wheel might not be adequate to move so broad a circular wick, I sometimes apply two double-ratchet regulators upon the outer and opposite sides of the cylinders or semicircular tubes, cutting through the outer plates of the latter, so as to allow the ratchets to come in contact with the outer surface of the wicks, and then work the regulators, as in the usual way, by a simple rotary motion.

a a, Fig. II, is the apron, which is attached to the top of the burner-case, 8 8, and extends down nearly to the fount on which the burner stands, and aids much in giving steadiness and portability to the flame.

Advantages.

First, this burner never heats, even to palpable warmth, and generates no gases, and consequently cannot explode.

Secondly, it produces the most brilliant light of any other light-producing structure in existence, and about one-eighth more light from a given quantity of oil than any other now known.

Thirdly, the flame and chimney both being round, all parts of the latter heat so nearly simultaneously that it is impossible to break a chimney with the flame or heat.

And, lastly, all concur in the opinion that this is the most compact, neat, and comely burner which has ever been produced.

What I claim as my invention, and desire to secure by Letters Patent, is—

The combination and arrangement of the concentric wick-tubes or plates 2 3, with open spaces *b b* therein, the movable wick-regulator 4, perforated plate *k*, and apron *a*, substantially as and for the purposes herein specified.
